UNITED STATES PATENT OFFICE

CARL H. BRICKER, OF DES MOINES, IOWA

SMOKING-TOBACCO CONTAINER

Application filed February 16, 1929. Serial No. 340,351.

The principal object of this invention is to provide a tobacco container that is capable of holding the tobacco in the top portion of the container, regardless of the amount of tobacco in the container.

More specifically, the object of this invention is to provide a tobacco container comprising the ordinary metal can, the paper package for holding the tobacco inside the can and hook members secured on the front of the package capable of engaging the upper marginal edge of the can for holding the package of tobacco at any elevation inside the can.

15 A still further object of this invention is to provide a means of elevating a package of smoking tobacco in a tobacco can that is economical in manufacture and durable in use.

20 These and other objects will be apparent to those skilled in the art.

My invention consists in the construction, arrangement and combination of the various parts of the device, whereby the objects contemplated are attained as hereinafter more fully set forth, pointed out in my claim and illustrated in the accompanying drawings, in which:

Fig. 1 is a side sectional view of the ordinary tobacco can and illustrates the manner in which my invention holds the package of tobacco inside the can at various elevations.

Fig. 2 is a front view of the ordinary smoking tobacco can with my invention being used therewith.

Fig. 3 is a rear view of one of the hook members for holding the package of tobacco in an elevated position inside the tobacco can.

40 Fig. 4 is a side view of one of these hook members and more fully illustrates its construction.

Fig. 5 is a front view of one of the hook members secured to a portion of the paper package for holding the smoking tobacco inside the metal can.

Most of the pipe smoking tobacco is sold in long can containers similar to the one shown in Fig. 1 and Fig. 2. The tobacco is tightly

packed in these cans and must be loosened with the finger or like before it will readily pour into the bowl of the pipe, or cigarette paper. This procedure is easily done as long as the can is full of tobacco, but when the 55 tobacco is low in the can, the finger is not long enough to extend to the bottom portion of the can and loosen the tobacco. Also it is possible to cut the hand on the sharp upper marginal edge of the tobacco can when attempting to reach far into the can. I have overcome these objections as will be appreciated by those skilled in the art.

I have used the numeral 10 to designate the ordinary tobacco can having the lid 11. 65 The numeral 12 designates the smoking tobacco in the can having around it the usual oil wrapping paper 13. It will readily be seen that if the wrapper 13 holding tobacco is elevated and held as the tobacco is used up, 70 the tobacco will always be in the upper portion of the can regardless of the amount of tobacco in the can. I have made this possible by a plurality of hook members, secured to and placed in a vertical row on the front 75 side of the wrapper as shown in the drawings. These hook members each comprise a base portion 14 and a hook portion 15 obtained by bending the upper portion of the base portion back upon itself as shown in Fig. 4. 80 These hook members are secured to the wrapper by arms, or clasps 16 cut out of the base portion when the hook member was made. These arms pass through the wrapper and are clinched on the inner side of the wrapper 85 by being bent either away from each other or toward each other. This is done by suitable machinery before the wrapper is placed around the tobacco.

The operation of my invention is easily 90 understood. When the tobacco becomes low, the package 13 is manually raised until the upper hook member engages the upper marginal edge of the can 11 and the now unnecessary upper portion of the wrapper torn off. 95 This procedure is repeated each time the tobacco gets low until the package 13 is completely elevated and the tobacco used up.

It will be noted that there is considerable distance between the upper part of the hook 100

portion and the point where the arms extend through the wrapper. The reason for this is to eliminate the possibility of accidentally tearing off the wrapper on a line where the arms pierce the paper, thereby releasing the hook member from the wrapper.

By the hook members being comparatively wide, the package of tobacco will be prevented from any lateral swinging movement in the can. The hook members should be made of suitable material such as sheet metal, in order that they will yieldingly and frictionally engage both sides of the rim of the can and yieldingly hold the package of tobacco from accidentally being elevated in the can, which often happens when the can is turned upside down to pour out the tobacco. When the lid 11 is closed the hook member, engaging the marginal edge of the can, is securely held from detachment with the marginal edge. The closing of the lid also tends to clamp the hook member on the marginal edge of the can.

Some changes may be made in the construction and arrangement of my improved tobacco container without departing from the real spirit and purpose of my invention and it is my intention to cover by my claim any modified forms of structure or use of mechanical equivalents which may be reasonably included within their scope.

I claim:

In combination with a tobacco container, a paper package for holding tobacco inside container, a plurality of base members spaced apart and secured vertically on said paper package, and a hook member on each of said base members each capable of engaging the marginal edge of said tobacco container for supporting said paper package at various elevations inside said tobacco container.

CARL H. BRICKER.
